UNITED STATES PATENT OFFICE.

OSWIN ROTTLOFF, OF AUERBACH, GERMANY.

STOCKING WITH LONGITUDINAL AND TRANSVERSE REINFORCEMENTS.

Application filed May 22, 1924, Serial No. 715,074, and in Germany November 30, 1923.

This invention relates to the arrangement of transverse and longitudinal reinforcements according to a pattern in hosiery, and especially in stockings and socks. Similar 5 reinforcements at the edge of the stockings have become known and also vertical stripes for patterning. According to this invention these transverse and longitudinal reinforcements are arranged in the leg and in the 10 foot of the stocking or in both these parts.

An embodiment of the invention is shown, by way of example, on the only figure of the drawing.

The longitudinal reinforcements *a* and 15 the transverse reinforcements *b* are always arranged both in one stocking and they do not only extend at right angles to one another but may also be at oblique angles to one another. The reinforcements may be 20 interrupted at certain points. At the points where the longitudinal reinforcements and the transverse reinforcements cross one an-

other double reinforced parts *c* are produced, wherefrom results a special advantage. If this special advantage is not desired the 25 threads of the longitudinal reinforcements are interrupted at either side of the transverse reinforcements.

Owing to this arrangement of reinforcing stripes the durability of the stocking is increased and the fit of the same on the leg is improved. Another advantage is that the ladders which occur in the leg or in the foot in the thin stockings worn at present do not run along the entire stocking but only a 30 35 short distance up to the next transverse reinforcement.

I claim:—

A stocking knit with body yarn and having knitted intersecting reinforcing stripes 40 which define therebetween areas knit with body yarn alone.

In testimony whereof I affix my signature.

OSWIN ROTTLOFF.
